ELECTRIC LAMP HOLDER MOUNTING

Chester J. Sternaman, Springfield, Ill.

Application March 3, 1950, Serial No. 8,297

Term of patent 14 years

(Cl. D48—31)

To all whom it may concern:

Be it known that I, Chester J. Sternaman, a citizen of the United States, residing at Springfield, Illinois, have invented a new, original, and ornamental Design for Electric Lamp Holder Mounting, of which the following is a specification, reference being had to the accompanying drawings, forming part hereof, in which:

Figure 1 is a front elevational view of an electric lamp holder mounting, showing my new design.

Figure 2 is a rear elevational view thereof.

Figure 3 is a side elevational view.

Figure 4 is a top plan view.

Figure 5 is a bottom plan view.

The broken lines shown in the drawing are for illustrative purposes only.

I claim:

The ornamental design for an electric lamp holder mounting, substantially as shown and described.

CHESTER J. STERNAMAN.
